UNITED STATES PATENT OFFICE.

JOHN A. TOPPING, OF CHICAGO, ILLINOIS, ASSIGNOR TO THE BARBER ASPHALT PAVING COMPANY, OF PHILADELPHIA, PENNSYLVANIA, A CORPORATION OF WEST VIRGINIA.

FLEXIBLE SHINGLE.

Application filed February 23, 1922. Serial No. 538,495.

To all whom it may concern:

Be it known that I, JOHN A. TOPPING, a citizen of the United States, residing at Chicago, in the county of Cook and State of Illinois, have invented certain new and useful Improvements in Flexible Shingles, whereof the following is a specification, reference being had to the accompanying drawings.

10 This invention relates to roof coverings and more particularly to shingles of the type which are fabricated from sheets of fibrous material, such as felt, paper, or the like, previously treated with a bituminous substance 15 such as asphaltum, whereby the shingles are rendered flexible, non-porous and waterproof, so as to shed the rain and to retain warmth within the building covered thereby. An object of the invention is to provide 20 shingles of this type which are formed, so as to be inter-engaging when properly laid upon a roof, to prevent the edges of the shingles from rising under wind pressure to prevent the accumulation of snow and moisture 25 under the edges of the shingles, and to compel the shingles to lay tight and flat upon the roof at all times. This is accomplished in the present invention by integrally forming certain portions of the shingles with means 30 to engage over the edges of adjacent shingles, thereby interlocking the assemblage and causing the shingles to coact to mutually hold down their edges.

The above stated objects may be accomplished in various ways, and I have devised several preferred embodiments of my invention, which are illustrated in the accompanying drawings:

Fig. I is a view in plan of a fragment of 40 a roof covering formed of a plurality of shingles, constructed in accordance with one embodiment of my invention.

Fig. II is a view in plan of an individual shingle illustrating to better advantage its 45 detailed construction.

Fig. III is a view in plan of a fragment of a roof covering constructed of shingles having the same structural formation, as those shown in the preceding figures, but 50 designed in the form of an equilateral quadrangle, so as to obtain a different visual architectural effect, and an arrangement requiring a minimum amount of shingles per unit area of roof to be covered.

55 Fig. IV is a view in top plan of a frag-

ment of a roof covering formed of shingles fabricated in accordance with my invention, in which the shingles are integrally connected in the form of strips to facilitate laying of the courses.

With reference to Figs. I and II of the drawings, 10 indicates an individual shingle designed in the usual form of a quadrangle having opposed sides of equal length, but adjacent sides of unequal length. Each 60 of the longer sides or edges is formed with a notch or slot 11, which enters at a point substantially midway of the ends of the shingle, but closer to one end than the other, hereinafter called the short end, and extends 65 into the edge of the shingle in a diagonal direction toward said short end for a sufficient distance to form a pair of pronounced tabs or flaps 12, both of which are directed toward the long end of the shingle. The 70 shingles shown in Fig. III are constructed in an identical manner, but are designed in the form of a square or equilateral quadrangle, and the notches 11 are formed in a reverse manner; that is, they extend diagonally toward the longer end, instead of toward the shorter end, as in the first form. This, however, is a matter of preference, and does not alter the principle underlying 75 the construction of these shingles.

In assembling the shingles to form a roof covering, the first course is laid, closely spaced, along the eaves in the usual manner, but with the tabs 12 extending upward or toward the ridge of the roof, as shown in 80 Fig. I. The next course is laid upon the first, overlapping the same for a considerable distance, with each shingle of the second course overlapping the adjacent margins of a pair of shingles of the first course to secure a 85 bond effect. In laying one course, over another, the tabs 12 on the shingles of the underlying course are slightly raised to permit the lower edges of the shingles of the covering course to be inserted thereunder, thus 90 causing the lower edges of the shingles to lay flat or tight against the roof, and interlocking the same, one with another. The fastening elements 13 are preferably driven through the shingles of the covering course 95 at points opposite the notches, so as to enter the underlying shingles also penetrating the latter at points adjacent the margins of their long ends. The fastening elements will 100 thus be covered and protected from the 105 110

weather. It will be noted that since the extent to which the covering shingles overlap the underlying shingles is definitely limited by the seating of the edges of the former in the notches of the latter, each course forms a guide for the next, so that the shingles may be readily laid in straight lines without the use of guides or other shingle laying paraphernalia. The style of shingle shown in Fig. III is laid in the same manner, except that the shingles of each course are preferably spaced relatively to a greater extent than in the assemblage of the first style shown in Fig. I. As a result, fewer shingles per unit area of roof are required and a slightly different visual architectural effect is obtained.

For convenience and the saving of time in laying shingles, I may employ the expedient of fabricating shingles embodying the above mentioned improvements in the form of a strip, so that an entire course may be laid at a time, as shown in Fig. IV. The strip 14, constituting a course, is formed along one edge with uniformly spaced transverse slots 15 which extend to the longitudinal medial line of the strip at which point each slot is intersected by a substantially crescent shaped slot 16, the ends of which extend equi-distantly toward the slotted edge of the strip to form a pair of tabs or flaps 17 projecting in an opposite direction. The provision of the transverse slots 15 defines a plurality of spaced shingle ends 18, all of which are integrally connected at their underlying or upper edges. In use, these strips are laid, one upon another in partial overlapping relation to form the courses of a shingled roof covering, arranging the courses relatively, so that the shingle ends 18 of the covering course each span the adjacent margins of a pair of shingle ends of the next underlying course to produce a bond effect. The tabs or flaps 17 are lifted so as to extend over the lower edges of the next covering course of shingles. It will be seen that by this arrangement the act of laying the shingles is facilitated to the

highest degree, since the strip formation enables an entire course to be laid at one operation, and the seating of the edges of the covering shingles into the notches of the underlying shingles permits the courses to be readily laid in parallel in a short space of time without the use of guides or the like.

In each of the forms described above, the exposed edges of the shingles are engaged at not less than two points so that they are caused to lay flat. Owing to the stiffness of the material from which the shingles are manufactured, the tabs 12 or 17, as the case may be will be sufficiently rigid to hold down the shingles against ordinary wind pressure and will effectively prevent, to a great extent the accumulation of snow or sleet under the exposed edges of the shingles as well as exclude the entrance of moisture beneath the shingles to a point short of the underlying rafter covering.

Having thus described my invention, I claim:

1. A flat shingle of flexible bitumen impregnated material of rectangular form, having opposite edges slotted diagonally toward one end of the shingle to form oppositely extending tabs lying in a plane coinciding with the plane of the shingle, but capable of being flexed away to engage over the edge of an overlying shingle.

2. A roof covering, comprising a strip of flexible bitumen impregnated material having one longitudinal edge slotted transversely to form shingle ends, each shingle end having its side edges slotted diagonally toward its end edge to form oppositely extending tabs lying in a plane coinciding with the plane of the strip, but capable of being flexed away to engage over the edge of an overlying shingle end.

In testimony whereof, I have hereunto signed my name at Chicago, Illinois, this 31st day of January, 1922.

JOHN A. TOPPING.
